UNITED STATES PATENT OFFICE

2,563,484

VALVE

Edmond Ojalvo, New York, N. Y.

Application July 16, 1949, Serial No. 105,130

1 Claim. (CL 277—31)

1

This invention relates to valve structures, and particularly to the type wherein a closure is effected by the engagement of two complementary conical members.

A common type of valve of the category above-mentioned employs a movable valve member with an outer conical surface engageable with a correspondingly proportioned conical valve seat. Such valves are intended to provide an extended closure surface in contradistinction to the type of valve in which the closure is effected by a relatively thin circumferential engaging surface. In such conventional structures, it is generally found expedient to employ a spring arrangement for yieldably holding the two conical surfaces into pressing engagement. This is generally accomplished by attaching a spring to the base of the male valve member, the spring extending downwardly through the underlying female cavity for anchorage therebelow. With such an arrangement it is deemed inadvisable to permit the flow of water to proceed from below the female cavity upwardly because of the obstructing spring arrangement and its anchorage; and it is hence necessary to limit such conventional devices to arrangements where the water inlet is positioned above the female valve seat.

It is within the contemplation of my invention to provide a valve structure in which coacting male and female conical valve members are employed, and yet which will permit a flow of inlet water centrally through the female valve seat, and which will also obviate the use of the spring arrangements, above-mentioned.

And it is a further object of my invention to provide, in a valve structure of the above category, means for maintaining the coacting complementary valve members in firm pressing engagement, whereby a secure valve closure is effected.

Still another of my objectives is to provide two coacting conical valve members wherein one member is rotatable with respect to the other, and where there is a minimum of frictional engagement therebetween. And in this aspect of my invention it is an object to provide a "floating" arrangement whereby there is no contact between the base portions of said two coacting members during an operative rotation of one with respect to the other.

A further object of my invention is to provide relatively simple means for limiting the operative rotational movement of one of said coacting valve members with respect to the other.

Still a further object of my invention is to

2

provide means for selectively setting an auxiliary valve to determine the desired rate of flow without actuating the main valve. And in this aspect of my invention it is an important object to enable such flow regulation to be manually effectuated while the main operating valve is in its closed condition.

Other objects, features and advantages will appear from the drawings and the description hereinafter given.

Referring to the drawings,

Figure 1 is a longitudinal sectional view, partly in elevation, of a preferred form of my invention, the valve being shown in closed position.

Figure 2 is a fragmentary view like Figure 1, the valve being shown in open position.

Figure 3 is a view substantially like Figure 1, but in open position, and with the auxiliary valve in an unobstructing position and the auxiliary regulating handle in raised unlocked position.

Figure 4 is a section of Figure 1 taken along line 4—4.

Figure 5 is a section of Figure 3 taken along line 5—5.

Figure 6 is a fragmentary section of Figure 1 taken substantially along line 6—6.

Figure 7 is a front elevational view of the two conical main valve members in coactive relation.

Figure 8 is a side view of Figure 7, and

Figure 9 is a section of Figure 7 taken along line 9—9.

In the preferred form of my invention illustrated in the drawings, the device is arranged with an upper hand manipulatable portion generally designated as 10 disposed above the sink floor 11, the body portion 12 of the valve being shown below the said floor.

The casing 13 has a bottom inlet pipe extension 14 internally threaded to receive therein an inlet supply pipe (not shown). Disposed within the casing 13 is the male conical valve member 16 containing an annular base flange 17 resting upon the bottom shoulder 18 of the casing, and having an externally threaded base extension 19 in threaded engagement with the casing extension 14. Valve member 16 contains an axial bore 20, the lower portion 21 thereof constituting an outlet passage communicating with the two diametrically opposed radial outlet passages 22 and 23.

The upper portion 24 of the bore 20 is threaded along a portion thereof for operatively accommodating the auxiliary valve 25 to be hereinafter referred to.

Rotatably disposed over male valve member 16 is the female conical valve member 26, the in-

ternal conical surface 21 of which is proportioned to fit the outer surface 28 of member 16. Member 26 also contains in its lateral wall the two diametrically opposite outlet apertures 29 and 30 adapted for registry with the said outlet passages 22 and 23 when valve 26 is in its predetermined open position.

Connected with valve 26 is the hollow main valve stem 31, the upper portion 32 being splined to receive thereover the internally splined inner boss 33 integral with the main handle member 34 containing an apron 35 and finger-engaging extension 36, the apron overlapping the ring 37 threaded on to the upper portion of casing 13. The top of handle member 34 contains the internally threaded recess 38 within which is disposed the flanged bushing 39 the downwardly extending boss 40 of which is in threaded engagement with the upper inner wall 41 of the main valve stem 31. The flange 42 of the bushing, which rests on the floor of recess 38, contains a plurality of intersecting diametral recesses 43 adapted for interlocking engagement with the rib 44 of the regulating handle 45, said rib being disposed on the underside of the flanged base 46 positioned within recess 38 and underlying the retainer ring 47 in threaded engagement with the lateral wall of recess 38.

Handle 45 contains an axial recess 48 of polygonal cross-section into which extends the correspondingly shaped upper end 49 of the auxiliary valve stem 50 carrying said auxiliary valve 25, said valve stem 50 extending through the central aperture 51 of the bushing 40.

Packing 52 is disposed upon the upper shoulder 53 of the female valve 26, the packing ring 54, in threaded engagement with casing 13, being in pressing engagement with the packing. The male valve 16 contains at the upper portion thereof of the cavity 55 accommodating therein the packing 56 between the lower ring 57 and the upper ring 58 in threaded engagement with the lateral wall of cavity 55.

The said base flange 17 is notched along a portion of its periphery; and in the particular embodiment of my invention illustrated, the flange contains the peripheral notched portion 59 extending along one-half of the circumference of the flange, thereby presenting two opposite stop walls 60 and 61. Extending downwardly from the bottom of female valve member 26 is the peripheral lug 62 engageable with the stop walls 60 and 61 upon an operative rotation of said member 26. In the embodiment illustrated, lug 62 is approximately one-quarter of the circumference of the bottom of member 26, so that the walls 63 and 64 of the lug will engage the stop walls 60 and 61, respectively, upon quarter turns of valve member 26. As indicated in Figure 7, when walls 60 and 63 are in engagement, the passages 22 and 23 are in operative registry with the apertures 29 and 30, respectively, and accordingly when walls 61 and 64 are in engagement, the valve is closed.

It is most important to note that the coacting valve members 16 and 26 are so proportioned that the lower edges 65 and 66 are spaced above and are never in engagement with the upper edges 67 and 68 of the base flange 17 of the male valve member 16. This "floating" arrangement of the female valve permits extensive engagement thereof with the male valve; yet it prevents a frictional engagement and grinding of the said upper and lower edges of the valve members 16 and 26. However, despite the avoidance of contact be-

tween said upper and lower edges, there nevertheless is positive operative contact between the lug 62 and the stop walls 60 and 61 of the base flange 17.

In the operation of this device, the auxiliary valve 25 must first be set for the desired flow. Auxiliary handle 45 is raised until base 46 engages the retaining member 47, thereby removing the rib 44 from its locking engagement with an underlying grooved portion 43 (see Figure 3). Handle 45 is now free to turn, and a regulating turning movement thereof will cause stem 50 to rotate, to raise or lower auxiliary valve 25 with respect to the outlet passages 22 and 23. Thus, if a relatively small flow is required, the valve 25 is adjustably moved into obstructing relation to passages 22 and 23, as shown in Figure 1. If a greater flow is required, the valve 25 is operatively raised above said passages, for example, to the position shown in Figure 3. In either event, when the passages 22 and 23 are in registry with apertures 29 and 30, the flow will be up through passageway 21, out through passages 22 and 23, and from apertures 29 and 30 out through outlet pipe 70.

Once the adjustment of valve 25 has been effected, and the handle 45 permitted to drop into interlocking engagement with base 42, the setting will remain undisturbed until a new adjustment is made. Whenever water is required, all that need be done is to rotate main handle 34 to bring the outer female valve member 26 into open engagement with valve member 16, and water at the desired flow rate will enter pipe 70. And obviously, if two such units were to be combinatively employed, one for hot water and the other for cold water, a predetermined temperature of the resulting mixture can readily be effected.

It should be further noted that since the packing 52 is in constant yieldable engagement with valve member 26, a firm operable engagement is effected between the two coacting surfaces of said members 16 and 26. This arrangement eliminates the use of the complicated conventional spring mechanisms generally employed at the base of the casing to pull an upper male cone valve downwardly into an underlying conical seat, thereby also preventing the entry of water through the base of the casing.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except insofar as such limitations are specified in the appended claim.

I claim:

In a valve structure, a casing, an inlet portion therein, a centrally apertured conical male valve member secured to the casing at said inlet portion, the outer lateral surface of the member tapering inwardly and upwardly away from said inlet portion, a conical female member with an inner tapered surface disposed over and in rotatable engagement with said male member, said female member being rotatable between two limiting positions, one being a predetermined open position and the other a predetermined closed position, an outlet aperture in the lateral wall of said female member, a passageway in said male member communicating between the

central aperture therein and the said outlet aperture when the female member is in its said open position, and retaining means holding said female member in engagement with the male member, whereby the said female member is maintained against longitudinal displacement; further provided with a hollow main valve stem fixedly connected to the female member, a main handle member fixedly secured to the said main valve stem, an auxiliary valve disposed within and in threaded engagement with the central aperture in the male valve member, whereby upon an operative rotation of the auxiliary valve it will move longitudinally relative to the said passageway in the male member, an auxiliary valve stem connected to the auxiliary valve and extending through the said main valve stem,

and a handle connected to the auxiliary valve stem for regulating the position of the auxiliary valve.
